UNITED STATES PATENT OFFICE.

LEWIS A. SEXTON, OF NEWARK, NEW JERSEY, ASSIGNOR OF ONE-HALF TO
CHARLES MARSHALL, OF SAME PLACE.

GAME.

SPECIFICATION forming part of Letters Patent No. 651,811, dated June 12, 1900.

Application filed November 17, 1899. Serial No. 737,315. (No model.)

To all whom it may concern:

Be it known that I, LEWIS A. SEXTON, a citizen of the United States, residing at Newark, in the county of Essex and State of New Jersey, have invented certain new and useful Improvements in Games; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to provide an interesting and pleasurable game, to obtain a suitably and conveniently constructed apparatus for playing said game, and to secure other advantages and results, which may be hereinafter referred to in connection with the description of the working parts.

The invention consists in the improved game, in the apparatus for playing said game, and in the arrangements and combinations of parts of the same, all substantially as will be hereinafter set forth and finally embraced in the clauses of the claim.

Referring to the accompanying drawings, in which like letters of reference indicate corresponding parts in both views, Figure 1 is a plan view of the apparatus for playing my improved game; and Fig. 2 is an enlarged edge view of the same, the board being shown in central section upon a line at right angles to the line of folding.

In said drawings, *a* indicates the board upon which my new game is played, said board being preferably made in two halves *a' a'*, hinged together across the middle of the board, so that the board will fold upon itself into a doubled position, and thus reduce the size for transportation or storage, as well as protect the inner surface upon which the game is played. The said board is made of any thin and light material—such as pasteboard, wood, or the like—which is sufficiently stiff for the purpose, and upon the face of said board are printed or painted peculiar markings or rulings, as will next be described, for playing the game.

Extending entirely around the board at a suitable distance in from the edge are paral-

lel lines or rulings *b*, forming between themselves courses or paths along which men or pieces are to be moved. Transverse lines *c* divide said courses into blocks or spaces, over 55 any number of which a man or piece may be moved, as provided for. Said courses or paths are preferably four in number, and each player in playing the game uses four men, one for each course. These men are 60 started from a corner of the board, as at *d*, and after the player has succeeded in moving a man entirely around the board it goes into the central space *e*, inclosed by the courses, which is "home." A transverse row 65 of spaces at the middle of each side of the board, as at *f*, may be designated as "safety-spots," from which one player's men cannot be taken by those of another player.

To provide means for determining the number of spaces that each player shall move in turn, I provide at the center of the game-board a pointer or index *g*, pivoted at its middle to turn freely in a plane parallel to the board. Said pointer is pivoted upon a 75 vertical pin *h*, having an ornamental head *h'* and a shank passing through the pointer and being screwed or otherwise removably secured to a base-plate *i*, adapted to lie upon the upper surface of the game-board. A 80 washer *j* is placed upon the pin *h* between the pointer and the base-plate to secure sufficient play between the pointer and board.

The base-plate *i* is provided at its under side with two or more downwardly-projecting 85 pins or legs *i' i'*, said legs being adapted to enter perforations in the board, and thus support the pivotal index-pointer in proper relative position to the board. At the same time the pointer and its connected parts can be 90 detached or removed from the board when it is desired to fold said board into closed position.

The perforations in the board *a* to receive the pins *i'* are disposed on opposite sides of 95 the line of folding of the board, and thus when the pointer is in place and the pins inserted in said perforations the board is held against closing and the hinged joint stiffened. Said perforations are preferably provided 100 with eyelets *k* in any ordinary manner common to the art, so that the pasteboard will not

become worn or torn by the repeated insertion and removal of the pins i' .

Upon the board a and with a center coinciding with the point of pivoting of the pointer g I describe a dial l , over which the pointer is adapted to pass. Upon said dial are numerals arranged around the periphery upon sectors of the circle, and said numbered sectors may be interspersed with sectors upon 10 which are written directions to advance or retard a playing-piece. As the pointer is spun, therefore, the sector upon which it stops will indicate the move of the player. By this construction I avoid the use of dice or other 15 devices which are separate from the game-board, and therefore liable to fall to the floor or become lost, and instead provide a single integral game apparatus complete in itself. The attachment of the pointer to the board, 20 furthermore, operates to hold the board open in plane position and prevents its premature closure, either partial or entire. When the game is finished, the pointer is detached from the board by withdrawing its pins i' from 25 their sockets, and the board may then be folded.

Having thus described the invention, what I claim as new is—

1. The combination with the game-board a , 30 comprising hinged sections adapted to be

folded together, and having a dial thereon, of a revoluble pointer adapted to coöperate with the said dial, and a base-plate upon which said pointer is pivoted, the board being provided with perforations on opposite sides of 35 the line of folding and eyelets inserted therein, and the said base-plate having downwardly-projecting legs or pins adapted to enter said eyelets and fit closely therein, whereby the pointer is supported and the board is held open against folding when the pins are inserted, substantially as set forth.

2. The combination with the game-board a , adapted to be folded across the middle, and having a dial l , thereon and perforations on 45 opposite sides of the line of folding, of a pointer g , pivoted upon a plate, and said plate i , having downwardly-extending legs adapted to enter the said perforations in the board, whereby the pointer is held in proper relative 50 position to the board and the board is held open, substantially as set forth.

In testimony that I claim the foregoing I have hereunto set my hand this 31st day of October, 1899.

LEWIS A. SEXTON.
